HENRY ROUNDY, OF SAN FRANCISCO, CALIFORNIA, ASSIGNOR TO CALIFORNIA MARINE METALLIC-PAINT COMPANY, OF SAME PLACE.

Design No. 3,599, dated August 3, 1869.

DESIGN FOR A TRADE-MARK.

The Schedule referred to in these Letters Patent and making part of the same

To all whom it may concern:

Be it known that I, HENRY ROUNDY, of the city and county of San Francisco, State of California, have originated and produced a new Design for a Trade-Mark; and I do hereby declare that the following is a full, clear, and exact description of the same, reference being had to the accompanying drawing or photograph, making part of this specification.

The figure represented is a design of my production, and consists of a star with six points, 1, 2, 3, 4, 5, 6, two of which extend from each side in horizontal lines, and one point each projecting at vertical angles from the top and base. Back of the star is a sunburst, and in its centre appears, placed at an incline from two of the inner angles, a fouled anchor. At

the top of the design occur the letters "T R A D E," and below it the letters "M A R K."

My design is intended as a trade-mark for a composition of paint for ships' bottoms, for which Letters Patent of the United States have been allowed.

Having thus described my production or device, What I claim, and desire to secure by Letters Patent, is—

The design for a trade-mark herein set forth.

In testimony whereof, I have hereunto set my hand and seal.

H. ROUNDY. [L. S.]
